UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

JOURNAL-BOX-ALIGNING DEVICE.

Application filed May 21, 1927. Serial No. 193,341.

This invention relates to journal box aligning devices.

In railway practice it has been found that the journal boxes in trucks of the pedestal type have a decided tendency to rotate about the axes of the journals, thereby gouging out the guide faces of the pedestal jaws, eventually causing the boxes to assume a permanently tilted condition which interferes with the proper movement thereof. This condition is much aggravated in trucks provided with equalizer bars which bear upon the journal boxes, for under service conditions longitudinal movement of the equalizer bars exerts a marked tilting action upon the journal boxes, aggravating the condition mentioned.

An object of this invention is to provide a simple and efficient means for maintaining the journal boxes in vertical alignment in the jaws of the pedestals against the tendency of the same to be displaced, while permitting the required movement of the journal boxes, said means including elements connected to each journal box which extend to points remote from the journal box and pedestal jaws where they are engaged by guide means which co-operate therewith to permit movement of the journal boxes in a vertical direction only and to prevent tilting of the boxes about the axes of the journal or the box under service conditions.

Other and further objects of the invention will more fully and clearly appear from the description and claims hereinafter following.

In the drawings forming part of this specification, Figure 1 is a fragmentary side elevational view of a truck of the pedestal type, showing the invention in connection therewith. Figure 2 is a horizontal sectional view of the invention corresponding substantially to the line 2-2 of Figure 1. Figure 3 is a vertical sectional view of the invention corresponding substantially to the line 3-3 of Figure 2. And Figure 4 is a perspective detailed view of one of the guide elements used in connection with the invention.

As shown in the drawings, a portion of the frame proper of a pedestal truck is indicated at 10, said frame being provided with a plurality of pedestal members, only one of which is shown, each pedestal member comprising a body portion 11 and spaced jaws 12-12 providing guide faces 13-13 for the journal box 14 which is slidably mounted between the

jaws 12-12 and maintained in position by the bar 15. The jaws 12-12 of each pedestal are transversely slotted as indicated at 16 for the reception of one end 17 of an equalizer bar 18 which bears on top of the journal box 14 in the usual manner, a spring 19 being interposed between the equalizer bar 18 and the truck frame 10.

The construction thus far described, is of a type in common use, and no claim is made thereto except in combination with the invention hereinafter described. In the construction just described, the journal box 14 moves vertically in the pedestal jaws 12-12, certain necessary clearance being provided between the side walls of the journal box and the guide faces of the pedestal jaws. Under actual conditions in starting up, or stopping, the journal boxes are tilted about the axes of the journals because of the relative movement between the truck frame proper and the wheels and the equalizer bars, and when running, the movement of each journal tends to tilt the box in the direction of movement thereof. The tilting movement of the journal boxes, however caused, gouges out the guide faces of the pedestals and the journal boxes eventually assume permanently tilted positions, interfering with the proper operation of the boxes and necessitating early renewal of the pedestal members.

The present invention contemplates means for confining each journal box to vertical movement within the jaws of the pedestal to overcome the conditions above noted, and said means co-operate with each journal box and the truck frame proper to hold the box against this tilting movement. In carrying out the invention, the side walls of each journal box, at their outer ends, are provided with apertures adapted for the reception of trunnions 20-20, formed upon a detachable yoke 21. The yoke includes two separate parts 22-22, each of which includes a portion fitting along the side wall of the box, upon each of which one of the trunnions is mounted. Each yoke member also includes an angular portion indicated at 23, and the inner ends of the portions 23 are provided with vertically projecting extensions 24-24. The members 22-22, are oppositely disposed, and are detachably secured together by bolts 25, which in position maintain the trunnions 20-20 in the recesses in the walls of the journal box.

Secured in spaced relation with reference to the journal box and the jaws of the pedestal, is a guide member in the form of a bracket 26 secured to the body portion 11 of the pedestal by means of rivets. The outer surface of the bracket is provided with an extension providing an eye 27, rectangular in cross section, in which are mounted the extensions 24-24 on the yoke, said extensions 10 being slidably disposed between the walls forming the eye, and operating to prevent lateral movement of the extensions but permitting free vertical movement thereof, thereby preventing tilting movement of the 15 journal box.

In this construction it should be noted that the guide member 26 is located as far from the center of the journal box and journal, as practicable, and securely anchored, thereby providing the necessary clearance for movement of the extensions in the guide means, while permitting relatively small movement of the journal box in a tilting direction and hence successfully overcoming the 25 possibility of the box tilting in the pedestal jaws.

While I have herein shown and described what I consider the preferred manner of carrying out the invention, the same is merely 30 illustrative, and I contemplate all changes and modifications which come within the scope of the claims appended hereto.

I claim:

1. In a device of the character described, 35 the combination with a truck having pedestal jaws, and a journal box mounted in said

jaws for sliding movements; an equalizer bar bearing upon said journal box; elements rigidly connecting with said journal box and extending to a point spaced from said pedestal jaws and said box; and means co-operating with the end portions of said elements to confine the same to vertical movement. 40

2. In a device of the character described, the combination with a truck frame and a pedestal member comprising a body portion and jaws, said body portion being secured to said truck frame; a substantially rectangular journal box mounted in the jaws of said pedestal member for vertical movement; 45 yoke means closely embracing opposite side edges of said journal box and rigidly secured thereto, said yoke means having an elongated guide stem; and an elongated guide member fixed to said truck frame accommodating said stem, for vertical sliding movement only. 50

3. In a device of the character described, the combination with a pedestal member and a journal box slidably mounted between the jaws of said pedestal member; a two-part yoke having trunnions engageable in recesses in the walls of the journal box, said yoke being provided with extensions; means for detachably securing the parts of the yoke together; and means co-operating with the extensions on said yoke for confining said extensions to movement in a vertical direction. 55

In witness that I claim the foregoing I have hereunto subscribed my name this 17th day of May, 1927. 60

JOHN F. O'CONNOR.
